UNITED STATES PATENT OFFICE

LÉANDRE MOUSSIER, OF PARIS, FRANCE

FOOT OPERATED PLATEN LIFTING DEVICE FOR CALCULATING MACHINES

Application filed January 27, 1932, Serial No. 589,296, and in France February 25, 1931.

This invention relates to a foot operated platen lifting device for calculating machines.

With the calculating machines of the Burroughs type or of a similar type, the lifting of the platen after each operation is generally effected by hand. Repeated thousands of times in the course of a day's work this action involves both fatigue and loss of time.

10 The object of this invention is to provide a device adapted to enable the operator to effectuate the lifting and the lowering of the platen by means of a slight pressure with his foot on a pedal.

15 In order to make my invention more clearly understood, I have illustrated, as an example, an embodiment thereof in the drawings, wherein

Figure 1 is a front view and

20 Figure 2 an end view of a device constructed in accordance with my invention.

Said device is essentially constituted by a pedal A provided with an antagonistic spring and adapted to actuate, through a rod B and a lever C, a cam D the section of which is so designed that the lifting of the platen is obtained by a slight foot-pressure on the pedal A. When the foot pressure on the pedal is released, the platen returns to its normal position promptly but without any jerk or shock, due to support E carrying a rest with a buffer or shock absorbing spring.

25 As shown in the drawings, a support plate 15 is mounted on the table of the calculating machine. Plate 15 carries a cam support E and a shaft support or bracket 5. A stub shaft 4 is rotatably mounted on bracket or support 5 and has an arm C fixed to one end thereof and a curved arm 11 of spring steel 30 fixed to the other end thereof. The free end of arm C is connected by a rod or link B with a pedal A. The latter is pivotally supported in hangers 6 secured to the frame of the table. A spring 8 urges the free end of the pedal or treadle upwardly and a guide 9 limits the upward and downward movement of the pedal A.

35 With this structure it will be realized that a depression on the pedal A will cause shaft 4, as shown in Fig. 2, to move counter-clock-

wise, and the structure carried by the free end of lever arm 11 will be raised.

In accordance with the present invention, the knob on the shaft of the platen of the machine is replaced by an elongated knob 7. 55 As shown in Fig. 1, knob 7 is secured to the shaft 1 of the platen and carries a roller 2 loosely mounted thereon intermediate the ends thereof. Roller 2 is mounted in alignment with a cam D carried by the free end of the curved arm 11. The foot-shaped cam D is provided with an upper cam surface which engages the roller 2. This cam surface 16 is shaped so that as the cam D is raised part of the upward movement is translated into movement of the roller 2 radially away from the shaft 4. On lowering the cam D, the nearly vertical portion of the cam surface approaches the roller 2 and tends to absorb the shock of the descent of the roller. 60 To fully absorb the shock of the fall of the platen carrying roller 2, a cam element 17 is pivoted to the upper extremity of the support E. Cam 17 is provided with a recess carrying a spring pressed plunger 13, the outer end of which engages an adjustment screw 14. The cam surface of element E is engaged by a roller 3 positioned at the heel of the foot-shaped cam D. Now, as the cam D descends, the roller 3 engaging the cam surface of cam element E will cause the latter to rotate about its supporting pivot against the action of the spring engaging plunger 13. Obviously, the shock will be absorbed by this spring. It is apparent that the effectiveness of the spring can be varied by adjusting the position of screw 14. 65 70 75

The carriage can be operated in the transverse direction without the cam interfering with or hindering its motion.

80 The novelty of the device resides not in the pedal control but in the shape of the cam D and of the support E adapted to permit, on the one hand, the platen to be lifted by a slight pressure and, on the other hand, said platen to be returned to its normal position without any appreciable jerk or shock.

85 What is claimed:

90 1. A device for lifting and lowering the platen of a calculating machine of the Bur-

- roughs type, comprising a pivoted arm, means on the end of the arm adapted to engage and lift the platen upon upward movement of the free end of the arm, and means for absorbing the shock of lowering the platen comprising a spring actuated pivoted cam adapted to engage the means carried on the free end of the pivoted arm.
2. A device for lifting and lowering the platen of a calculating machine of the Burroughs type, comprising a pivoted arm, means on the end of the arm adapted to engage and lift the platen upon upward movement of the free end of the arm, means for absorbing the shock of lowering the platen comprising a spring actuated pivoted cam adapted to engage the means carried on the free end of the pivoted arm, and foot-actuated means for moving the pivoted arm.
3. A device for lifting and lowering the platen of a calculating machine of the Burroughs type, comprising a pivoted arm, a cam on the free end of the arm adapted to engage and lift the platen upon upward movement of the pivoted arm, a pivoted cam element mounted adjacent the cam on the free end of the pivoted arm, a roller on the cam carried by the pivoted arm adapted to engage the cam surface of the cam element, and resilient means urging the pivoted cam element into engagement with the roller and adapted to cooperate with the surface of the pivoted cam element to absorb the shock of descent of the platen.
4. A device for lifting and lowering the platen of a calculating machine of the Burroughs type, comprising a pivoted arm, a cam on the free end of the arm adapted to engage and lift the platen upon upward movement of the pivoted arm, a pivoted cam element mounted adjacent the cam on the free end of the pivoted arm, a roller on the cam carried by the pivoted arm adapted to engage the cam surface of the cam element, resilient means urging the pivoted cam element into engagement with the roller and adapted to cooperate with the surface of the pivoted cam element to absorb the shock of descent of the platen, and means for adjusting the effect of the resilient means.

LEANDRE MOUSSIER.
